UNITED STATES PATENT OFFICE.

EDWARD C. ALBRIGHT, OF CONNERSVILLE, INDIANA, ASSIGNOR TO INDIANA LAMP CORPORATION, OF CONNERSVILLE, INDIANA, A CORPORATION.

HEADLAMP CONSTRUCTION.

Application filed March 28, 1927. Serial No. 178,834.

This invention relates to head lamps suitable for motor vehicles and the like.

One object of the invention is to simplify the assembly of the various parts constituting the head lamp and to reduce the number thereof to a minimum and these of relatively simple or standard construction.

One feature of the invention consists in the door rim forming not only a support for the door closure, but also cooperating with other parts for retaining the same in position and for retaining or supporting the reflector within the casing.

The full nature of the invention will be understood from the accompanying drawings and the following description and claim:

Fig. 1 is a front view of the invention. Fig. 2 is a sectional view taken along the line 2—2 of Fig. 1 and in the direction of the arrows.

In the drawings 10 indicates a casing suitably mounted which is provided with a flange or shoulder 11 adjacent the front edge thereof. An annular seat 12 constitutes a continuation which is continued forwardly and telescopically receives an annular sealing or cushion ring 13 bearing against the rear face of the door or lens closure 14. An annular door rim bears upon the outer face of said closure at 15 and is provided with an enveloping portion 16 that extends rearwardly and is telescopically associated with the casing and particularly the annular seat 12. A curled or flanged edge 17 is adapted to abut the shoulder 11 and limit rearward movement of the rim relative to the casing 10.

The reflector 18 includes a central aperture 19 supporting a contact terminal plug receiving socket 20 adapted to receive a light bulb 21. The outer end of the reflector includes a rearwardly extending portion 22 forming with the forward extension 12 of the casing an annular channel in which is mounted the cushion ring 13. The reflector includes an outwardly extending peripheral flange 23 that constitutes a bearing seat for the rear end of the cushion ring 13.

In assembling the head lamp the reflector is positioned in the casing with the light bulb 21 secured in its socket. Cushion ring 13 is positioned in the annular groove formed between the casing and the reflector and the lens closure 14 is then mounted upon the

casing with the door rim. In the present form of the invention the annular seat 12 is shown provided with a plurality of socket depressions 24 each including an inclined face 25 although an annular groove may be employed. The forward face thereof bears against the peripheral flange 23 of the reflector and the other or rearward face thereof engages an abutment or equivalent in the form of a rivet 26 which has an inclined face 27 receivable by the same. The aforesaid in reality constitutes a construction by which bead 17 rests on seat 12, and the rim 16, by a downward movement, puts a pressure on closure 14 at point 15 and also cushion 13 is compressed between rear side of 14 and front of reflector flange. This flange is forced rearwardly against socket depressions 24 or annular ring if employed, thus compressing the parts through pressure of rivet 26 at 27 on rearward inclined face 25 thereof and at 15.

Two rivets 26 are illustrated and these are positioned in spaced relation and in place of a third rivet, a threaded bolt 28 having a conical end 29 is provided. A check nut or lock washer 30 cooperates therewith for locking bolt 28 in adjusted position, it having threaded engagement with the aperture in the door rim mounting the same. Unthreading of bolt 28 until it is removable from the depression 24 permits the door rim with the lens to be tilted upon the other two rivets until it sufficiently clears the casing to permit the two rivets to be released from the adjacent depressions 24, whereupon the entire construction can be readily disassembled. The formation of depressions 24 as shown instead of as an annular groove having an inclined wall is preferred since it prevents the closure from rotating about the axis of the reflector and thus eliminates possibility of unthreading of the screw 28 by vibration in the rolling movement thereof which would occur if the closure would so rotate. If desired, other forms of abutments 26 may be provided which may be formed integral with the door rim or may be rigidly secured thereto.

The invention claimed is:

In a head lamp having a reflector and a closure and including a casing and a door rim nonrotatively connected together, the combination of a locking connection therebetween comprising an annular seat on the

casing telescoped by the rim and telescopically receiving the reflector, said rim bearing on the reflector through the closure, a plurality of depressions in said seat extending inwardly and engageable by the reflector for limiting inward movement thereof, and inwardly extending members carried by said rim and radially receivable by and extending into said depressions, said members and said

10 depressions having a radially and inwardly directed wedging engagement for drawing

the rim casing, closure and reflector together in clamped relation, one of said members being relatively and radially movable with respect to the rim for independent movement toward and away from the adjacent depression for rim and closure connection and disconnection. ¹⁵

In witness whereof, I have hereunto affixed my signature,

EDWARD C. ALBRIGHT.
